(57) **CLAIM**

The ornamental design for a display screen or portion thereof with graphical user interface, substantially as shown and described.

DESCRIPTION

FIG. 1 is a front view of a display screen including a graphical user interface with an error icon in accordance with the present design; and,

FIG. 2 is an enlarged view of the error icon of FIG. 1 in accordance with the present design, encircled portion labelled as '2' and shown separately for completeness of illustration.

The broken lines provided in the drawings illustrate a display screen or portion thereof with graphical user interface and form no part of the claimed design.

1 Claim, 2 Drawing Sheets
